(57) **CLAIM**

The ornamental design for a headlight lens, as shown and described.

DESCRIPTION

FIG. 1 is a frontal perspective view of a left headlight lens attached to a vehicle, no part of the vehicle is claimed;
FIG. 2 is a perspective view of the left headlight lens;
FIG. 3 is a front elevation view of the left headlight lens;
FIG. 4 is a left side view of the left headlight lens;
FIG. 5 is a top plan view of the left headlight lens;
FIG. 6 is a bottom plan view of the left headlight lens;
FIG. 7 is a sectional view taken along the lines 7—7 in FIG. 3;

FIG. 8 is a sectional view taken along the lines 8—8 in FIG. 3;

FIG. 9 is a frontal perspective view of an alternative embodiment of the headlight illustrated in FIGS. 1—8, showing a right headlight lens attached to a vehicle, no part of the vehicle is claimed;

FIG. 10 is a perspective view of the right headlight lens;
FIG. 11 is a front elevation view of the right headlight lens;
FIG. 12 is a right side view of the right headlight lens;
FIG. 13 is a top plan view of the right headlight lens;
FIG. 14 is a bottom plan view of the right headlight lens;
FIG. 15 is a sectional view taken along the lines 15—15 in FIG. 11; and,

FIG. 16 is a sectional view taken along the lines 16—16 in FIG. 11.

The phantom lines are not a part of the claimed invention.

1 Claim, 16 Drawing Sheets
